RADIOFREQUENCY AMPLIFIER

Original application filed August 6, 1923, Serial No. 655,794, patented September 4, 1928, No. 1,682,874.
Divided and this application filed August 9, 1928. Serial No. 298,586.

This application is a division of application Serial No. 655,794 filed August 6, 1923, on which has issued Patent No. 1,682,874, Sept. 4, 1928.

5 The invention herein described relates to amplifiers for high or radio frequency currents and is particularly concerned with devices for coupling amplifier tubes in cascade.

It has for one of its objects the elimination 10 or minimizing of the effects of detrimental capacity and stray fields, and the production of an amplifier of greatly improved efficiency.

In accordance with one feature of the 15 invention the coupling transformer is rendered practically astatic, so that the effect of stray fields is eliminated or minimized.

In accordance with another feature of the 20 invention the arrangement of polarities in the windings is such that the tendency to regeneration or oscillation is minimized. Other features are set forth at length herein.

In the drawings Fig. 1 is a schematic diagram showing a simple form of apparatus 25 embodying the invention. Figs. 1a, 1b and 1c show alternative arrangements of certain features of Figs. 1, 2 and 6.

Figure 2 is a modified form in which the 30 astatic feature is included.

Fig. 3 is a more detailed diagram showing the physical construction of one type of 35 coupling transformer.

Figs. 4 and 4a show the structural features of another type of transformer embodying 40 the invention.

Fig. 5 shows the amplification characteristics secured by application of the invention.

Fig. 6 is a schematic diagram of a multiple 45 band amplifier.

One of the most serious limitations in the 50 design of radio frequency transformers, as usually practiced, is the fact that the secondary electromotive force is largely dissipated in stray capacities, so that only a fraction, and sometimes a small fraction, of it is useful in producing amplification. Usually it is considered impracticable to construct such a transformer having a step-up ratio, because the electromotive force gained by the step-up 55 ratio is frittered away in these stray capaci-

ties, including the capacity of the transformer itself. Such stray or effective natural capacities always exist between the coils, condensers and other parts of the apparatus and at radio frequencies their effects are important.

By means of the present invention I not only avoid the detrimental effect of capacity in the windings, but I utilize the capacity to produce an improved result. By means of 60 this invention I am enabled to construct a transformer of high efficiency with a step-up ratio.

Another difficulty in radio frequency amplifiers of the usual type is inter-action of 65 the various stages, when amplifiers are used in cascade, which reduces the effective amplification and tends to instability or oscillation of the system. An important feature of the present invention is an arrangement of windings 70 whereby the external field of the transformer is reduced to a minimum so that it becomes practically astatic and inductive disturbances are eliminated.

In the drawings Fig. 1 shows schematically 75 a simple embodiment of the invention, as applied to a radio frequency amplifier of three tubes. In the arrangement shown, two of the tubes A_1 , A_2 are used for radio frequency amplification and the third D as a detector. 80 When in the following I refer to amplifier tubes generically it will be understood that one of these may be used for detection as shown. T , T are transformers coupling the tubes in cascade, each including a primary 85 coil p and a secondary coil s . In the first transformer the outer terminal of the primary coil p is connected to the output terminal or anode of the first amplifier tube A_1 and the outer terminal of the secondary s is 90 connected to the input terminal or grid of the second amplifier tube A_2 . The second transformer is similarly connected to the second amplifier tube A_2 and the detector tube D . The primary and secondary coils are 95 wound or connected in opposite senses so that their outer terminals a and b respectively are at opposite potentials, instead of being at like potentials as is usual in the construction of such transformers. This feature is 100

indicated in the diagram by the sign $\pm$ on the primary terminal a , and $\pm$ on the secondary terminal b , indicating that the polarities of these terminals change in opposite 5 senses. The resulting potential difference between these terminals, which would ordinarily be detrimental, is utilized to assist instead of opposing the magnetic coupling. Thus the transformer may be so constructed 10 that the primary and secondary windings constitute in effect a condenser whose capacity augments or assists the magnetic coupling effect of the two windings, as will be explained. This inherent capacity of the 15 windings is indicated by the dotted capacity couplings C in the drawings, dotted lines being employed to indicate that the capacities, although physically and necessarily existent as capacities, do not necessarily require 20 separate structural elements, as usually employed, but may be inherent in the transformer structure. If desired an external condenser may be connected across the terminals a b to augment the inherent capacity 25 of the transformer windings as shown at 8 in Fig. 1e. This capacity, whether inherent in the windings or external, assists the magnetic coupling of the transformer. It may be so chosen that its effective reactance at the 30 preferred operating frequency is approximately equal to the combined reactances of the coils ps , so that the transformer becomes in effect an oscillating circuit psC , tuned 35 approximately to such frequency, due allowance being made for the capacities of the associated tubes when these are material with respect to the capacity of the transformer. The result of this arrangement is that the 40 full potential difference between the terminals a b is effective in coupling the output of one tube with the input of the next. It will be understood that the capacity referred to, whether inherent in the transformer structure or provided in whole or in part by a 45 separate structural element, is not detrimental, as are the coil capacities in other arrangements, but is useful in increasing the effectiveness of the device inasmuch as under the present invention the capacity coupling tends to augment or assist the inductive 50 coupling of the windings and its capacity reactance tends to neutralize or may completely neutralize the inductance reactance of the windings.

55 The windings ps may be similar, in which case the useful secondary potential will be much larger than that of an equal ratio transformer not embodying this invention, but preferably the secondary is made with more turns than the primary so that a step-up ratio is secured.

60 The significance of this arrangement will be seen more clearly by reference to Fig. 1a, which is a simplified schematic diagram showing the relations of one pair of tubes

to the coupling system. The inductance of the coupling system comprises the inductance of the primary coil p and that of the secondary coil s , together with their mutual inductance, and the capacity C is the inherent or the total capacity of the system. The oscillating system psC is tapped at three points, a , b , and o , point o being the negative bus or neutral point. The input electromotive force is applied between a and o , and the output electromotive force is taken off between points b and o . The ratio between the input and output electromotive forces is determined by the inductive drops across coils p and s , which may be given any desired value within wide practical limits by suitably proportioning the coils.

70 To secure the best results it is usually desirable to shunt the external connections of the transformers including batteries, resistances, etc., by bridging condensers such as c_a whose capacity reactance in the working range of frequency is small. These serve to by-pass the high frequency oscillations across the inner terminals of the transformers, avoiding external loss by completing the closed circuit including the windings ps and the mutual capacity of the coils by the shortest possible route. Other bridging condensers such as c_b may be used when desired to bypass the output current of one tube and the 80 input current of the next to the filament or ground bus.

85 Fig. 2 shows an improved arrangement 90 which includes the features contained in Fig. 1 and has in addition an astatic feature whereby the external field of the transformer is practically eliminated. In this arrangement each of the coils of the transformer is made in two sections, wound or connected in opposite directions so that their external fields oppose and neutralize each other. In the primary the two sections are p_1 p_2 and in the secondary the two sections are s_1 s_2 . The section p_1 is arranged preferably in close inductive relation with the section s_1 and the section p_2 in close inductive relation with the section s_2 , so that a relatively close coupling is obtained between primary and secondary through their unbalanced internal fields, notwithstanding the opposing relations of the two halves of these windings which cause their external fields to balance and neutralize each other. The sections 95 p_1 s_1 are wound or connected in opposite 100 senses, as explained in connection with Fig. 1, and the same is true of the sections p_2 , s_2 , so that the external terminals a b will have 105 opposite polarities as in the arrangement of Fig. 1. The physical dimensions and relative positions of the coils may be so chosen, as in the case of Fig. 1, that the effective 110 capacity between the terminals a b has a reactance at the preferred operating frequency 115 approximately equal to the inductance 120 of the coupling system. The inductance of the coupling system comprises the inductance of the primary coil p and that of the secondary coil s , together with their mutual inductance, and the capacity C is the inherent or the total capacity of the system. The oscillating system psC is tapped at three points, a , b , and o , point o being the negative bus or neutral point. The input electromotive force is applied between a and o , and the output electromotive force is taken off between points b and o . The ratio between the input and output electromotive forces is determined by the inductive drops across coils p and s , which may be given any desired value within wide practical limits by suitably proportioning the coils.

reactance, so that at this preferred frequency the maximum effective potential difference is obtained between terminals *a b*.

In this arrangement it will be noted that 5 while the mutual induction of the two windings is relatively large, their external magnetic field is negligible. Since the potentials of the terminals *a b* are opposite, the stray electrostatic fields are also reduced to a minimum 10 so that undesired couplings are practically eliminated. This arrangement of windings also offsets the reversal of polarity occurring in the amplifier tube, so that 15 all tubes have like polarities, and the tendency to regeneration or oscillation by mutual interaction is avoided.

There are various forms of construction 20 that can be used in carrying out the invention. One of these is shown in Fig. 3, in which cylindrical or solenoidal windings are used. Here the primary coil is made 25 in two halves, $p_1 p_2$, wound in opposite directions as shown, and the secondary coil is also wound in two opposing halves $s_1 s_2$ as indicated. The primary and secondary coils 30 are shown separated for clearness of illustration of the windings. In operation the primary coil is placed inside the secondary, or vice versa, and the dimensions of the 35 windings and diameters of the tubes are so chosen that the capacity between windings has the requisite value. The drawings show also the direction of winding of the coils which gives the opposite potentials at the external terminals *a b*.

Figs. 4 and 4a show another type of winding 40 in which the coils are in disc form. These coils are wound preferably in slots of suitable thickness between three insulating discs E, clamped together with central spacers F forming a core on which the coils are wound. The slot for the secondary is preferably made wider than that of the primary so that the secondary has a larger 45 number of turns. The coils are constructed by winding first the desired number of turns in one direction for the inner half of the coil, as p_1 , then winding silk thread to form a spacer G and finally winding the second 50 section of the coil p_2 in the opposite direction. The same construction is used in the secondary coils $s_1 s_2$, though in this case preferably the number of turns in each section 55 is greater.

The dimensions of the coils and the distance between them are so chosen that the capacity has the desired value in relation to the inductance of the windings.

60 Either of the constructions shown in Figs. 3, 4 and 4a may be used for the transformers TT in Figs. 2 and 6, or any other suitable construction preferably embodying the feature herein described, may be used.

65 The principle of operation of this inven-

tion is capable of a wide variety of applications.

By winding the transformer coils with low resistance the apparatus may be made highly selective, so that the transformer circuit 70 with its inherent and associated capacities is resonant to a definite frequency and the amplification is high for this frequency but low for any other frequency. The characteristic curve of such a transformer is shown at a^5 75 in Fig. 5, in which the ordinates represent the ratio of amplification and the abscissas represent the frequency.

On the other hand, where an amplifier is desired which works effectively over a wide 80 range of frequencies I prefer to wind the transformer coils, or particularly the secondary coil, of relatively high resistance; for example by winding them of very fine 85 copper or larger German silver wire. Or the resistance may be inserted externally; for example, it may be placed effectively in series with the bridging condenser C_b , between the inner or low potential terminals 90 of the windings, as shown at R, Fig. 1b. This resistance, whether inherent in the winding or inserted, has the effect of lowering the peak of the amplification curve without materially lowering its amplitude at frequencies different from the resonant frequency, so that a broad characteristic is secured without corresponding loss in efficiency, as shown for example at b^5 in Fig. 5. A certain amount of resistance is also effective 95 in preventing the tendency to regenerate or oscillate which may occur when a number 100 of amplifiers are used in cascade.

The degree of coupling between the coils is also an important factor in determining 105 the amplifier characteristics. Where a broad characteristic is desired I prefer to make the coupling as close as practicable. Where a sharply selective characteristic is desired a looser coupling is permissible. It will be understood that the use of a loose coupling 110 is equivalent to increasing the effective ratio of turns. By suitably proportioning the coupling and resistance, as well as the inductance and mutual capacity of the windings, the characteristics of the amplifier may be 115 determined at will. The factors set forth in the foregoing for securing a sharply selective characteristic, namely, employing a step-up ratio of turns, and increasing the effective ratio of turns by decreasing the coefficient of coupling, have the result of increasing the input conductance at resonance 120 as will be readily understood. It will be understood also that any conductance shunted across a resonant circuit, such as the plate conductance of the associated vacuum tube, will increase the damping and decrease the selectivity of such a circuit, unless the shunted conductance is substantially lower than the input conductance of such circuit across 125 130

which such shunted conductance is connected. A substantially flat combined or overall characteristic may be obtained over a desired band of frequencies by the use of amplifier units in cascade having individual characteristics which are different. For example, Fig. 5, at c^5 , shows a typical characteristic of a three stage band amplifier. The curves in broken lines 1, 2, 3 show the characteristics of the three individual units including tubes and transformers or other coupling means that are connected in cascade, while the full line curve 4 represents the resultant or overall band characteristic of the combined system.

The different characteristics of the individual units of a band amplifier may be determined by the design of the windings, or characteristics like those shown in 1, 2, 3 at c^5 in Fig. 5 may be obtained from transformers of identical windings by suitably choosing the distance between the coils and the resulting mutual capacity or by other suitable means. Separating the coils by a dielectric spacer or otherwise raises the peak frequency of the characteristic curve by diminishing the capacity and the coupling.

Another convenient means of adjusting the characteristic of a transformer at will is by the use of condensers. Three ways of doing this are shown in Fig. 1c. The first is by shunting an external condenser 8 across the outer terminals a, b, of the primary and secondary coils p_1 p_2 s_1 s_2 . This external capacity is in effect added to the inherent mutual capacity of the coils, and so lowers the frequency characteristic. The second arrangement consists in connecting a condenser 9 in parallel with the primary coil p_1 p_2 . This has a result equivalent to increasing the effective inductance of the primary coil and consequently it lowers the frequency characteristic. A similar result is obtained by connecting a condenser 10 across the secondary coil s_1 s_2 , but the effect of such capacity is proportionately greater than when the same capacity is added at 9 if, as I prefer, the transformer coils p_1 p_2 s_1 s_2 have a step-up ratio.

The condensers or capacities 8, 9, 10 may be used singly or in any desired combination, and any or all of them may be made variable. An effective arrangement for tuning the coupling transformers is secured by designing the transformers to have a sharply selective characteristic and inserting a variable condenser at 9.

A particularly useful modification of the band amplifier is shown in Fig. 6. Here are three transformers with their corresponding tubes arranged in cascade. These transformers are preferably designed to have overlapping characteristics as shown at c^5 in Fig. 5, giving a combined band characteristic which is flat. It will be observed from this figure

that when the spacing of the individual characteristics is suitably related to the width or form of the characteristics, the resultant characteristics of over-all amplification is a substantially flat band with a sharp cut-off at each side. The desired spacing may be secured by any of the means herein described for determining the frequency characteristic of the amplifier, or by any other suitable means. This characteristic is shifted in the frequency coordinate by adding impedances to the transformer systems, preferably by the use of small condensers 9' 9'' of suitably proportioned capacity so arranged that they may be shunted successively across the transformers. These condensers are cut in and out by switches S' S'', the switches S' S' S'' being arranged to be operated simultaneously, for example by mounting them on a common rock shaft 11 operated by a handle or lever 12. Similarly the switches S'' S'' S''' operate simultaneously. When the switches S' are closed by rocking the shaft, cutting in the condensers 9', the characteristics of all the transformers are changed in frequency so that the combined characteristic is a flat topped band displaced in the frequency coordinate as shown at 6 in part d^5 Fig. 5. Additional condensers 9'' may be switched on by a further movement of the rock-shaft 11, closing the switches S'', and in this way the operating range of the amplifier may be broadened as far as desired. Preferably the capacities of the condensers 9' 9'' are so chosen that the bands 5, 6, 7 have a slight overlap, as shown.

This arrangement has numerous advantages. An amplifier is secured which gives practically uniform amplification over a wide range of frequencies, and the sub-division of this range into a plurality of narrower bands is useful in eliminating interference from signals of undesired frequencies, since the amplifier is highly effective for frequencies within its band but excludes almost completely frequencies outside of this band. By this means extremely feeble signals may be received without interference from the most powerful nearby stations.

While I prefer to shunt the band-shifting condensers 9', 9'' across the primary coils p_1 p_2 as shown, they may be placed, if desired, in any of the positions 8, 9, 10, shown in Fig. 1c.

The flatness of the band of effective amplification and the sharpness of the cut-off for frequencies outside this band, which characterize the preferred form of my invention, are secured by so relating the spacing of the characteristics of the several amplifier stages to the width and form of the characteristics as to secure the particular overlap that is required for the characteristic employed. This relation is illustrated in Fig. 5, c^5 , which shows curves for a three-stage amplifier.

Considering the relation of these curves at different frequencies, it is noted that for a frequency less than the peak frequency of the characteristic 1, characteristic 3 shows

5 substantially no amplification and the over-all characteristic is small. As the frequency is increased, all the component characteristics are increasing simultaneously, and the amplification rises very sharply up to a frequency corresponding to the peak of curve 1. At this frequency curve 1 begins to fall while the others rise more slowly, and, by virtue of the particular spacing employed, the rise of one curve substantially offsets the fall of 15 another, so that the amplification is substantially uniform, up to a point corresponding approximately to the peak of curve 3, beyond which all of the curves are descending. The resultant characteristic descends with a very sharp cut-off.

It will be noted that while all of the component characteristics are selective, their cut-off is gradual in the manner that is usual in resonance curves. In the case of the over-all band characteristic 4, however, the cut-off is sharp—much sharper than the slope of the component characteristics—so that the width of the curve at its base is not materially greater than that of the component characteristics, notwithstanding the breadth and flatness of the band at its top.

This is of great importance since it permits a high degree of selectivity due to the sharp cut-off, notwithstanding the width of 35 the band of effective amplification.

The flatness of the band depends upon the spacing. If the spacing is closer than the optimum, the over-all characteristic will be peaked. If the spacing is broader than the optimum, the over-all characteristic will have a central valley. Usually the optimum spacing is secured for a 3-stage amplifier when the high and low frequency characteristics (3 and 1, Fig. 5, c⁶) intersect and overlap at a point corresponding to about half the maximum amplification. For other amplifiers the optimum spacing is readily determined by computation or graphic methods.

50 What I claim is:

1. In an amplifier for high frequency currents, a plurality of amplifier tubes, a polarity reversing inductive coupling between these tubes, and a capacity shunting the polarity reversing inductive coupling.

2. In an amplifier for high frequency currents, a plurality of amplifier tubes, a polarity reversing inductive coupling between these tubes and a capacity whose reactance is approximately equal to the inductance reactance of the coupling means shunting the polarity reversing inductive coupling.

3. In an amplifier for high frequency currents, a plurality of amplifier tubes and a polarity reversing inductive coupling between

these tubes comprising coupled inductances having an inherent mutual capacity tending to assist the magnetic coupling of the inductances.

4. In an amplifier for high frequency currents, a plurality of amplifier tubes, a polarity reversing inductive coupling between these tubes comprising closely coupled inductances having an inherent capacity tending to neutralize the reactance of the inductances. 70

5. In an amplifier for high frequency currents, a plurality of amplifier tubes, a polarity reversing inductive coupling between these tubes comprising coupled inductance coils having a step-up ratio and an inherent capacity tending to neutralize the reactance of the inductances. 75 80

6. In an amplifier for high frequency currents, a plurality of amplifier tubes, coupling transformers connecting the amplifier tubes in cascade, having reversed windings whereby the reversal of polarity that is inherent in the tubes is again reversed in the coupling means, so that all the successive tubes have similar polarities. 85 90

7. In an amplifier for high frequency currents, a plurality of amplifier tubes, coupling transformers connecting the amplifier tubes in cascade, having reversed windings whereby the reversal of polarity that is inherent in the tubes is again reversed in the coupling means, so that all the successive tubes have similar polarities, and capacities shunting the windings of the transformers. 95 100

8. In an amplifier for high frequency currents, a plurality of amplifier tubes, coupling transformers connecting the amplifier tubes in cascade, having reversed windings whereby the reversal of polarity that is inherent in the tubes is again reversed in the coupling means, so that all the successive tubes have similar polarities, and capacities shunting the windings of the transformers having a reactance at the preferred operating frequency approximately equal to the effective inductance reactance of the transformer windings. 105 110

9. In an amplifier for high frequency currents, a plurality of amplifier tubes, coupling transformers connecting the amplifier tubes in cascade, having reversed windings whereby the reversal of polarity that is inherent in the tubes is again reversed in the coupling means, so that all the successive tubes have similar polarities, the windings of the transformers being so proportioned and arranged as to have a mutual capacity tending to assist the magnetic coupling of the windings. 115 120

10. In an amplifier for high frequency currents, a plurality of amplifier tubes, coupling transformers connecting the amplifier tubes in cascade, having reversed windings whereby the reversal of polarity that is inherent in the tubes is again reversed in the coupling 125 130

means, so that all the successive tubes have similar polarities, the windings of the transformers being so proportioned and arranged as to have a mutual capacity reactance approximately equal to the inductance reactance of the windings.

11. In an amplifier for high frequency currents, a coupling comprising an inductance connecting the output terminal of one tube with the input terminal of the next and made in two sections inductively coupled and wound so that their outer terminals are of opposite potentials, a capacity shunting the inductance having a reactance approximately equal to the inductance reactance and a neutral or bus connection to the sections between the input and output terminals.

12. In an amplifier for high frequency currents, a plurality of amplifier tubes and between these tubes a coupling coil connecting these tubes in cascade and wound in sections whose external fields are mutually reversed, these sections being so arranged that their external fields oppose and neutralize each other.

13. In an amplifier for high frequency currents, a plurality of amplifier tubes and between these tubes a coupling transformer connecting these tubes in cascade and comprising primary and secondary coils each wound in two sections whose external fields are mutually reversed, each section of the primary being coupled to the corresponding section of the secondary, these couplings being so arranged as to assist each other while their mutually reversed external fields oppose and neutralize each other.

14. In an amplifier for high frequency currents, a plurality of amplifier tubes and between these tubes a coupling transformer connecting these tubes in cascade and comprising primary and secondary coils each wound in two sections whose external fields are mutually reversed, each section of the primary being coupled to the corresponding section of the secondary, these couplings being so arranged as to assist each other while their mutually reversed external fields oppose and neutralize each other, the primary and secondary coils being wound to produce opposite potentials at the input and output terminals.

15. In an amplifier for high frequency currents, a plurality of amplifier tubes and between these tubes a coupling transformer connecting these tubes in cascade and comprising primary and secondary coils each wound in two sections whose external fields are mutually reversed, each section of the primary being coupled to the corresponding section of the secondary, these couplings being so arranged as to assist each other while their mutually reversed external fields oppose and neutralize each other, and a ca-

pacity shunting the windings of the transformer.

16. In an amplifier for high frequency currents, a plurality of amplifier tubes and between these tubes a coupling transformer connecting these tubes in cascade and comprising primary and secondary coils each wound in two sections whose external fields are mutually reversed, each section of the primary being coupled to the corresponding section of the secondary, these couplings being so arranged as to assist each other while their mutually reversed external fields oppose and neutralize each other, the primary and secondary coils being wound to produce opposite potentials at the input and output terminals, and a capacity whose reactance is approximately equal to the effective inductance reactance of the transformer windings at the preferred working frequency.

17. In an amplifier for high frequency currents, a plurality of amplifier tubes, polarity reversing inductive coupling means connecting these tubes in cascade, each coupling means having a capacity shunting the windings which substantially neutralizes the inductance reactance at a given frequency, said frequencies being different for the several coupling means which have overlapping response curves so related to each other that the combined amplifying effect of the system is substantially uniform over a given band of frequencies.

18. In an amplifier for high frequency currents, a plurality of amplifier tubes, coils connecting these tubes in cascade, each coil being wound in sections whose external fields oppose and neutralize each other, and a capacity shunting each coupling coil which substantially neutralizes the effective inductance reactance at a given frequency, said frequencies being different for the several coils which have overlapping response curves so related to each other that the combined amplifying effect of the system is substantially uniform over a given band of frequencies.

19. The method of amplifying high frequency currents which consists in amplifying the current energy, inductively reversing the polarity of the amplified output, shunting the direct and reversed polarity points by a capacity, and combining cumulatively the inductance and capacity output.

20. The method of amplifying high frequency currents which consists in amplifying the current energy, inductively reversing the polarity of the amplified output, shunting the direct and reversed polarity points by a capacity, thereby neutralizing the polarity reversing inductance, and combining cumulatively the inductance and capacity output.

21. The method of amplifying high frequency currents which consists in amplifying the current energy, inductively reversing

the polarity of the amplified output, and shunting the reversing inductance by a capacity whose reactance is approximately equal to the reactance of the reversing inductance.

22. The method of amplifying high frequency currents which consists in amplifying the current energy, producing by the output energy a polarity reversing induction current and a substantially equal and opposite capacity current, producing by combination of these currents an increased reversed potential, and utilizing this potential.

23. In an amplifier for high frequency currents, a plurality of amplifier tubes, a coupling between the output terminal of one tube and the input terminal of the next tube, and an astatic inductance included in said coupling having sections wound and related in opposite senses to cause their external fields to oppose and neutralize each other, thus avoiding undesired coupling, and to have an unbalanced internal field constituting an effective inductance.

24. In an amplifier for high frequency currents, a plurality of amplifier tubes, a coupling between the output terminal of one tube and the input terminal of the next tube, and an astatic inductance included in said coupling made in four sections inductively coupled in pairs so that the input and output terminals are at opposite potentials, the coupled pairs being wound and related in opposite senses to cause their external fields to oppose and neutralize each other, thus avoiding undesired coupling, and their internal fields to constitute an effective inductive coupling.

25. This specification signed this 26th day of July, A. D. 1928.

FREDERICK K. VREELAND.
